UNITED STATES PATENT OFFICE.

FRANK L. IRWIN AND JOHN E. TESSEYMAN, OF COLUMBUS, OHIO, ASSIGNEES TO THE
RALSTON STEEL CAR COMPANY, OF COLUMBUS, OHIO, A CORPORATION OF OHIO.

RAILWAY-CAR.

977,405.

Specification of Letters Patent. Patented Nov. 29, 1910.

Application filed June 6, 1910. Serial No. 565,170.

To all whom it may concern:

Be it known that we, FRANK L. IRWIN and JOHN E. TESSEYMAN, citizens of the United States, residing at Columbus, in the county 5 of Franklin and State of Ohio, have invented certain new and useful Improvements in Railway-Cars, of which the following is a specification.

This invention relates to railway cars and 10 more particularly to dumping cars, the object of the invention being to provide a car having hinged bottom sections together with means for effectively controlling the movement of said sections and for locking said 15 sections in their closed positions without undue strain upon the locking parts.

Further objects and advantages of the invention will be set forth in the detailed description which now follows.

20 In the accompanying drawings, Figure 1 is a view partially in longitudinal section and partially in side elevation of a dumping car constructed in accordance with the invention, Fig. 2 is a partial plan view therefore 25 of with one of the hinged bottom sections broken away, Fig. 3 is an end elevation of said car, and, Fig. 4 is a transverse vertical section of a portion of said car with some of the parts omitted.

30 Like numerals designate corresponding parts in all of the figures of the drawing.

Referring to the drawings, the numeral 5 designates the car truck, 6 the side walls and 7 the end walls of the car body. The floor 35 of the car comprises a plurality of transverse sills, said sills comprising channel beams 8 and horizontal floor plates 9. A longitudinally extending truss 10 has secured thereto at intervals, brackets 11, these

40 brackets being located at the center line of the car. Hingedly connected to these brackets are swinging floor sections 12 and 13 and it is in the means for controlling the movement of these floor sections that the present 45 invention more particularly resides.

Extending transversely of the car at intervals, are webs 14 and 14^a. Bearing plates 15 are secured to the faces of these webs and together with bearing brackets 16, provide 50 supports for longitudinally extending shafts 17 and 18. Mounted to swing loosely upon the outer ends of these shafts are levers 19 and 20, these levers carrying pawls 21 and 22, which engage ratchet wheels 23 and 24.

To prevent retrograde movement of the 55 shafts during the time that the doors are being moved to their closed positions, pawls 25 and 26 are pivoted to the end wall of the car and engage ratchet wheels 27, only one of which is shown.

60 The swinging sections 12 have their side and outer edges 28 and 29 downturned for the purpose of strengthening these sections and rendering them rigid. Brackets 30 carried by these swinging sections, have anti-friction rollers 31 pivotally mounted thereon, these rollers bearing upon the upper side of levers 32. The outer ends of these levers are slotted at 33 for the reception of a pivot 34 which pivotally and slidably connects 70 said lever to bearing members 35 carried by the adjacent transverse beams. The lever 32 has its upper face curved as shown and is provided with a hook extension 36. A slot 37 is formed in the inner end of each of the 75 levers 32 for the reception of a pin 39 which pivotally and slidably connects the lever to a link 40. The opposite end of this link is pivotally connected at 41 to a crank 42 which is fast upon the shaft 17, it being understood 80 that this structure is duplicated at each side of each of the door sections. It is to be noted that the link 40 is provided with a shoulder 43 (see Fig. 4).

85 The operation of the device is as follows: When it is desired to lower the door sections to thereby discharge the contents of the car, the pawls 25 and 26 are moved out of engagement with their ratchet wheels 27 and 28 and movement is imparted to the shafts 90 17 and 18 by means of the levers 19 and 20 and the pawl and ratchet wheels 21, 22, 23, and 24.

95 Referring to Fig. 4 particularly, the direction of movement of the shaft 17 will be in the direction of the arrow. This will swing the crank 42 first upwardly and then over toward the left, the pivot 39 sliding in the slot 37 and the lever 32 by reason of its slotted engagement with the pivot 34 sliding 100 bodily toward the left in Fig. 4 until the crank passes over the center, whereupon the door sections, the lever 32, the link 40 and the crank 42 will drop to the position illustrated in dotted lines in Fig. 4 and the contents of the car will be discharged. It is 105 apparent that since the movements of the levers 19 and 20 are entirely independent of

each other, the contents of one side of the car may be discharged independently of the other side thereof.

When it is desired to again close the doors, 5 the pawls 25 and 26 are moved into engagement with the ratchet wheels 27 to prevent retrograde movement of the shafts and the shafts are rotated to return the parts to the position illustrated in full lines in Fig. 10 4 and since the operation of all of the door controlling mechanisms is the same, the operation will be described with relation to the structure shown in full lines in Fig. 4. It will be noted that when the parts are 15 dropped to the dotted line positions shown in Fig. 4, the roller 31 lies in the hook 36 and the door is thereby supported in its lowermost position.

When the shaft 17 is started to rotate toward the right in Fig. 4, to return the parts to the full line position, the link 40 follows the crank 42 until the shoulder 43 abuts against the shaft; continued rotation of the crank will then rock the link 40 upon the 25 fulcrum provided by the shaft 17 and shoulder 43, the movement of the lower end of the link 40 causing the pivot 41 to travel to the left-hand end of the slot 37 and causing the lever 32 as a whole, to travel upwardly and 30 outwardly to its limit of movement toward the left. Continued movement of the crank will ultimately bring the parts to the full line position shown in Fig. 4, at which time the pivots 39 and 41 are in alinement with each 35 other and with the shaft 17 and the crank 42 is on its "dead center." The doors are then positively located in their closed positions and the weight of the doors tends to hold the shafts 17 and 18 against rotation, 40 rather than to tend to rotate said shafts. These parts form in fact a powerful toggle mechanism which provides great leverage to aid the operator in closing the doors and which positively locks the doors against 45 opening after they have reached their closed positions, as will be readily understood.

From the foregoing description, it will be seen that simple and efficient means are herein provided for accomplishing the objects 50 of the invention, but while the elements shown and described are well adapted to serve the purposes for which they are intended, it is to be understood that the invention is not limited to the precise construction set forth, but includes within its 55 purview such changes as may be made within the scope of the appended claims.

What we claim, is:

1. The combination with a car body, of a 60 plurality of floor sections hingedly connected thereto, a rotative shaft arranged beneath said floor sections, pivotally and slidably mounted levers located beneath said floor sections and upon which said sections bear, 65 crank arms on the shaft, and links con-

necting said arms with the levers, said links being adapted to bear against the shaft when the doors are closed.

2. The combination with a car body, of a plurality of floor sections hingedly connected thereto, a rotative shaft arranged beneath said floor sections, pivotally and slidably mounted levers located beneath said floor sections and upon which said sections bear, cranks on the shaft, links connecting the 70 shaft and levers, anti-friction members carried by the floor sections and bearing upon the levers, and a hook extension at the inner end of each of said levers, with which the anti-friction member engages when the door 80 is in its lowermost limit of movement.

3. The combination with a car body, of a plurality of floor sections hingedly connected thereto, a rotative shaft arranged beneath said floor sections; a pivotally and slidably mounted lever located beneath said floor sections and upon which said sections bear, and toggle mechanism connecting said levers and said shaft, said toggle mechanism comprising a crank fast upon the shaft, a link one 85 end of which is pivotally connected to said crank and the other end of which is slidably engaged with said lever.

4. The combination with a car body, of a plurality of floor sections hingedly connected thereto, a rotative shaft arranged beneath said floor sections, pivotally and slidably mounted levers located beneath said floor sections and upon which said sections bear, and toggle mechanism connecting said levers and said shaft, said toggle mechanism comprising a crank fast upon the shaft, a link one 90 end of which is pivotally connected to said crank and the other end of which is slidably engaged with said lever.

5. The combination with a car body, of a 105 drop door, a lever pivotally connected with the underframe of said car at its outer end and forming a support for said door, the inner end of said lever having a slot and a member engaging said slot to support the 110 inner end of the lever and thereby support the door in closed position.

6. The combination with a car body, of a drop door, a pivot member projecting from the underframe, a lever having a slot in its 115 outer end portion through which said pivot member passes, said lever forming a support for the door, the inner end of the lever being provided with a slot and a member engaging said inner end slot to support the 120 inner end of the lever and thereby support the door in closed position.

In testimony whereof we affix our signatures in presence of witnesses.

FRANK L. IRWIN.
JOHN E. TESSEYMAN.
